A. D. STERN,
OIL TRANSFER DEVICE,
APPLICATION FILED APR. 18, 1921.

1,421,319.

Patented June 27, 1922.

Albert W. Stern, INVENTOR:
BY Niederheim & Fairbank
ATTORNEYS.

UNITED STATES PATENT OFFICE.

ALBERT D. STERN, OF PHILADELPHIA, PENNSYLVANIA.

OIL-TRANSFER DEVICE.

1,421,319.

Specification of Letters Patent. Patented June 27, 1922.

Application filed April 18, 1921. Serial No. 462,378.

To all whom it may concern:

Be it known that I, ALBERT D. STERN, a citizen of the United States, residing in the city and county of Philadelphia, State of Pennsylvania, have invented a new and useful Oil-Transfer Device, of which the following is a specification.

My invention consists of a device for transferring or distributing oil from a storage tank to a supply tank of an automobile or other vehicle, the same embodying an air chamber member, means for supplying air under pressure to the latter, an oil discharge pipe adapted to pass through said chamber into said tank and permit the air under pressure to enter said tank, a nut-like member on said tank, a sleeve adapted to couple said air chamber with said nut-like member, a neck or branch pipe carrying a cock or spigot, and a nut-like member on said air chamber adapted to couple said neck with said oil discharge pipe, the nut-like member on the tank being adapted to firmly support the appurtenances of the device on said first named nut-like member, and consequently on said tank, as will be hereinafter more fully described.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a partial side elevation, and partial vertical section of an oil transfer device embodying my invention.

Figure 2 represents a vertical section of a portion thereof on an enlarged scale.

Similar numerals of reference indicate corresponding parts in the figures.

Referring to the drawings.

1 designates a tank adapted to contain a supply of oil which is to be transferred elsewhere. 2 designates a hollow member whose interior forms the air chamber 3 passing through which is the adjacent portion of the oil discharge pipe 4 which is of less diameter than that of the chamber 3 and has its main portion occupying the tank 1, its lower end being open and above the bottom of said tank.

Screwed to the lower portion of said member 2 is the threaded sleeve 5 which is also screwed to the nut 6, the latter being adapted to be screwed to the wall of an opening

7 in the top of the tank 1. The inner diameter of the sleeve 5 is greater than that of the inclosed portion of the pipe 4, so that the interior of said sleeve is in communication with the air chamber 3. 60

Connected with the side of the coupling 2 is the tube 8 which leads from a supply of air under pressure and directs the air into the chamber 3 and from thence through the sleeve 5 and nut 6 into the tank 1 so as to subject the oil in the latter to the action of the air under pressure. 65

Screwed to the upper end of the member 2 is the nut 9 which has the upper end of the pipe 4 screwed to it, said nut 9 having also screwed to it the tubular neck or branch 10 whose interior is in communication with that of the pipe 4, said nut 9 thus serving to couple the neck 10 with the oil discharge 75 pipe 4.

On the outer terminal of the neck 10 is the discharge cock or faucet 11 it now being noticed that the nut 6 sustains on the tank 1 the sleeve 5, the member 2, the air conveying tube 8, the nut 9, the neck 10 and the cock 11, thus providing simple and inexpensive means for accomplishing the same. 80

The operation is as follows:—

When it is required to transfer or distribute the oil from the tank to an automobile or other vehicle requiring the same, the cock 11 is opened when the air under pressure in the tank forces the oil therein into the pipe 4 and from thence into the neck 10 90 and the cock 11 and so it may be directed from the latter wherever desired, this being accomplished in a convenient and rapid manner and without leaking at the tank.

When the cock is closed, the transfer or distribution of the oil from the tank 1 ceases immediately. 95

Having thus described my invention what I claim as new and desire to secure by Letters Patent, is:—

1. In an oil transferring device of the character stated, a tank, an oil discharging pipe therein in communication therewith, a hollow member forming an air receiving chamber adapted to be in communication 105 with a source of air under pressure, a discharge neck in communication with said pipe, a nut-like member engageable with said chamber and adapted to connect said neck with said hollow member and pipe, 110 and a nut-like member connectible with the wall of said tank to support said chamber,

pipe, discharge neck, and appurtenances, and to connect them with said tank.

2. An oil transferring device of the character stated consisting of a tank, an oil discharging pipe therein in communication therewith, an air receiving chamber adapted to be in communication with a source of air under pressure, a portion of said pipe being within said chamber and exteriorly of less diameter than the interior of the latter, a sleeve connectible with the lower end of said air chamber, a portion of said pipe being within said sleeve, the interior diameter of the latter being of greater diameter than 10 that of the exterior of said portion, a tu-
15 bular discharge branch, a nut-like member engageable with said air receiving chamber, and said nut-like member adapted also to couple said branch with said discharge pipe, a cut-off member on said discharge branch, 20 and a nut-like member engageable with said sleeve and a wall of said tank, said last named member being adapted to connect the appurtenances above the same with said tank and to support them on the latter.

ALBERT D. STERN.
